UNITED STATES PATENT OFFICE

118,248

DESIGN FOR A WINDOW FRAME

Zoltan Roseman, Cleveland, Ohio, assignor to Violet Roseman Saunt, Cleveland, Ohio

Application August 7, 1939, Serial No. 86,491

Term of patent 14 years

To all whom it may concern:

Be it known that I, Zoltan Roseman, a citizen of the United States, residing at 14924 Kinsman Road, in the city of Cleveland, county of Cuyahoga and State of Ohio, have invented a new, original, and ornamental Design for a Window Frame, of which the following is a specification, reference being had to the accompanying drawing, forming a part thereof.

Figure 1 is an isometric drawing of a window frame embodying my design. The rear of the frame is plain; the frame taken along the lines and in the direction of the arrows 2-2 of the Figure 1. The left side of the frame is the same excepting that it is faced in the opposite direction;

Figure 3 is a top sectional view of the frame taken along the lines and in the direction of the arrows 3-3 of the Figure 1; and

I claim:

The ornamental design for a window frame, substantially as shown and described.

ZOLTAN ROSEMAN.
